CURTAIN STRETCHER CLAMP

Filed Feb. 6, 1926

Inventor:
Charles G. Carlson,
By: Damning Damning
J. H. S.

UNITED STATES PATENT OFFICE.

CHARLES G. CARLSON, OF CHICAGO, ILLINOIS.

CURTAIN-STRETCHER CLAMP.

Application filed February 6, 1926. Serial No. 86,404.

This invention relates to clamps for use in securing the corners of curtain stretcher frames and the like, and the object of the invention is to provide a clamp which will 5 securely hold the adjoined rails of the curtain frame against slipping when the clamp is tightened under moderate pressure, which is desirable in order to avoid the need for excessive exertion in tightening up the 10 clamps, and also to avoid the imposition of heavy pressures which might tend to crush or mar the wood of the curtain frame rails.

Another object of the invention is to so arrange the parts that they may be readily 15 stamped out of strips or plates of metal and readily assembled at a minimum cost.

A further object is to provide means for certainly and effectively guiding the pressure element in the clamp, so that it will 20 slide freely under the thrust of the adjusting screw, and to otherwise improve the construction and arrangement of the device as a whole.

In the drawing:

25 Figure 1 is a corner of a curtain frame showing the clamp of the present invention in clamping relation;

Fig. 2 is an enlarged elevation of the part shown in Fig. 1, taken at right angles 30 to the disclosure of said figure;

Fig. 3 is a cross sectional view taken on line 3—3 of Fig. 2, looking in the direction of the arrows; and

Fig. 4 is a side elevation of a modified 35 form of clamp.

The clamps of Figs. 1, 2 and 3 are of generally U-shaped formation comprising side plates 10 and 11, the latter of which is of greater length than the former, which side 40 plates are connected by a cross head 12, best shown in Fig. 3. The side plates 10 and 11 are secured to the front and rear faces respectively of a frame rail 12 by provision of rivets 13 and 14 respectively, the latter of which passes only through the extended rear plate 11. This furnishes a loop shaped fitting in the form of an extension 45 rigidly secured to the frame rail 12' in position to receive the end of the adjoined frame rail 15.

The clamp is provided at its head end 50 with an adjustable abutment 16 comprising an inner contact plate 17 adapted to abut squarely against the outer edge of the frame rail 15, which contact plate has backwardly turned therefrom a pair of spaced parallel

guide walls 18 which are somewhat narrower in width than the contact plate save at the extreme outer ends where said walls are laterally extended to afford stop shoulders 60 19. The guide walls 18 lie within cuts or recesses 20 in the proximate edges of the cross head 12 which thus furnish guideways for the in and out adjusting movements im- 65 parted to the abutment.

The abutment is adapted to be adjusted by means of a screw 21 having a handle or thumb piece 22 at its outer end, which screw is threaded through the center of the cross head 12 and bears directly against the center 70 of the back face of the contact plate 17, so that by turning the screw, the abutment will be forced inwardly to the extent permitted by the stop shoulder 19. The arrangement 75 is one which affords movement within the limits measured by the length of the narrow portions of the guide walls 18, and, at the same time, prevents loss or displacement of the abutment member when out of contact with the frame rail.

In order to provide ample clearance for the movable pins 22 which travel in the undercut channel 23, the overlying bridge portion 24 of the front plate 10 is slightly elevated which affords the necessary clearance for the pins without unduly deepening the undercut channel in which the pins are guided. In order to afford sufficient stock for the threading of the adjusting screw 21 through the head 12, the metal of the head, 80 at the point adjacent to the threaded bore, is flanged inwardly to afford a boss 25 which serves to extend the threading sufficiently to ensure a full threaded engagement with the screw.

In the modification illustrated in Fig. 4, the clamp comprises front and rear plates 26 and 27 with a cross head 28, but in this instance, the rear plate 27 only is rigidly secured to the frame rail 12 by the provision of rivets 29. This leaves the front plate 26 free to be clamped against the front face of the frame rail 15 by the tightening up of a thumb nut 30 on the front end of a draw bolt 31, which draw bolt extends through the front and rear plates and serves to draw them together when the nut is tightened up.

The clamp of Figs. 1 to 3 is very effective in affording a tight clamping action 110 between the rails by reason of the fact that the abutment member affords a broad flat

surface of contact with an extended area along the edge of the rail 15, so that under moderate pressure, the engagement will be sufficiently firm to tightly hold the parts together without any tendency to crush the wood or to center the pressure at a single point, and, at the same time, adequate means are provided for guiding the adjusting movements of the abutment in such a way as to prevent binding or cramping. Furthermore, the contact plate 17, the edges of which bear squarely against the inner faces of the front and rear plates 10 and 11, is strengthened and reinforced so that there is no bending or buckling against the rearwardly turned guide walls 18, which thus not only subserve a guiding function but also impart strength and rigidity to the fitting.

20 I claim:

1. In a clamp for curtain frames or the like, the combination of spaced plates connected at their outer ends by a cross head provided with guide slots in its exposed edges, an abutment member comprising a

contact face plate subtending the space between the plates and rearwardly extending walls embracing and guided within the slotted edges in the cross head and terminating in laterally extending shoulders projecting beyond the slots in the cross head to limit the sliding movement of the abutment member, and an adjusting screw entered through the cross head and bearing against the rear surface of the abutment member, substantially as described.

2. In a clamp for curtain frames and the like, the combination of spaced plates connected at their upper ends by the cross head provided with guide slots in its exposed edges, an abutment member comprising a contact face plate subtending the space between the plates, and rearwardly extending walls embracing and guided within the slotted edges in the cross head, and an adjusting screw entered through the cross head and bearing against the rear surface of the abutment member, substantially as described.

CHARLES G. CARLSON.
